United States Patent Office

Des. 178,947
Patented Oct. 16, 1956

178,947

COMBINED BRUSH AND COMB HOLDER

Robert J. Bachmann, New York, N. Y.

Application September 30, 1955, Serial No. 38,178

Term of patent 7 years

(Cl. D4—3)

FIG. 1.

FIG. 2.

FIG. 3.

I claim:

The ornamental design for a combined brush and comb holder, as shown.
